TRAFFIC SIGNAL

Raymond W. Glawe, Acampo, Calif.

Application July 28, 1936, Serial No. 93,109

4 Claims. (Cl. 177—327)

This invention relates to a traffic signal primarily adapted for use on automobiles or self-propelled vehicles.

It is particularly aimed to provide a construction which is exceedingly compact and which utilizes a signal member normally retracted and wrapped about a drum or the like.

It is further aimed to provide a novel structure wherein the drum is adapted to be actuated by an electric motor and which drum and associated parts are carried by a frame adapted to be electromagnetically tilted or moved to different angles or positions so that the same signal arm or the like will have different signalling meanings such as right turn, left turn and stop.

The more specific objects and advantages will become apparent from a consideration of the description following taken in connection with accompanying drawings illustrating an operative embodiment.

In said drawings:—

Figure 1 is a view in horizontal section illustrating my improvements;

Figure 2 is a vertical sectional view taken on the plane of line 2—2 of Figure 1;

Figure 3 is a detail section taken on the line 3—3 of Figure 2;

Figure 4 is a detail section taken on the line 4—4 of Figure 1;

Figure 5 is a detail view taken on the plane of line 5—5 of Figure 1, and

Figure 6 is an electrical diagram of the parts.

Referring specifically to the drawings wherein like reference characters designate like or similar parts, 10 designates a suitably shaped attaching bracket, adapted to be screwed, bolted or otherwise fastened as at 11 to a suitable part of an automobile 12. Said bracket 10 is horizontally disposed and it suspends and pivotally mounts a frame 13 with which trunnions 14 and 15 are integral or rigidly connected. Said trunnions 14 and 15 are journaled in the arms of the attaching bracket 10 and an armature 16 is integral or rigid with the trunnion 15. Rigidly secured to an arm 13a mounted on frame 13, and on opposite sides of the armature 16 are solenoids or electromagnets 17 and 18.

Rigidly connected to the frame 13 as by means of screws 19 is an electric motor 20 of the direct current, reversible type. Journaled around the electric motor 20 is a drum 21 having a hub 22, concentric with the main or driven shaft 23 of the motor, the ends of which shaft are preferably journaled in the frame 13.

Anchored at one end to the periphery of the

drum 21 is a signalling member 24. Such signalling member is a steel or other metallic ribbon, which is flexible, and normally arcuate in cross section. Such ribbon however in flat transverse form or cross section is wrapped about the periphery of the drum 21, maintained flat about such drum and guided with minimum friction by means of rollers 25 contacting with the signalling member. Said motor, drum and signalling member are enclosed by a casing 26, to which the rollers 25 are journaled and which casing is suitably secured to the frame 13.

Said casing 26 has an enlargement or offset at 27 provided with an opening 28 which is arcuate in shape and conforms to the normal and operative cross sectional arc of the signalling member. Such tape 24 also passes through an opening 29 in the casing proper, which opening 29 is nearly straight but slightly arcuate. It will be understood that normally a short portion of the free end of the signalling member 24 projects beyond the opening 28 and the construction is such that the tape cannot be wound sufficiently on the drum to pull the free end of the tape 24 inwardly out of the opening 28. It will be understood that when the tape or signalling member 24 is in its normal cross sectionally arcuate condition, that it will maintain such shape and serve as a signalling arm as shown in Figures 1 and 4. Obviously the tape may be shaped as desired, for instance pointed at the free end, and it may be painted or ornamented in any desired manner and if preferred, of luminous paint or material thereon.

The shaft 23 has a pinion 30 keyed thereto enmeshed with a larger pinion or gear 31 keyed to a shaft 32 journaled in the frame 13 and which shaft carries a smaller pinion 33 enmeshed with a pinion 34 keyed to the hub 22 of the drum 21. A suitable stop mechanism is shown at 35 to limit the turning of the parts so as to prevent retraction of the signalling member 24 at its free end inwardly of the opening 28.

The electric motor 20 may receive its energy from any desired source and usually from the starting, lighting and ignition storage battery 36 of the automobile or vehicle with which the invention is associated, a circuit being suggested at 37 in Figure 6. One side thereof is grounded as at 38. The other side thereof is in the form of a switch 39 grounded as at 40. The said circuit also includes the said solenoids 17 and 18 and contacts 42, 43, 44, and 45.

Generally speaking, the closing of the circuit operates the motor 20 so as to project the signal

member 24 and at the same time, except in the case of a left turn, one or the other of the solenoids 17 and 18 is energized so as to rock the frame 13 and all parts connected thereto to vary the angle of the projected signal 24 as suggested in Figure 4. More specifically, if the switch arm 39 engages the contacts 42 and 41, the motor 20 will be energized as well as the solenoid 18, the motor thus projecting the signal 24 and the energized solenoid 18 attracting the armature 16, whereby the frame 13 and all parts carried thereby will be rocked so that the signal 24 will be at an angle above the horizontal. Should the switch 39 engage the contacts 42 and 43, said motor 20 will be energized to project the signal 24 and at the same time the electromagnet 17 will be energized which will attract the armature 16, tilting or swinging the frame 26 and all parts carried thereby and moving the projected signal 24 to the position below the horizontal as suggested in Figure 4 and which position indicates stop. When the switch 39 engages the contact 44, it simply energizes the motor 20, causing projection of the signal 24 to indicate a left turn, such signal being horizontal and the frame 13 and associated parts being so suspended from the trunnions 14 and 15 as to normally hang in a position where the signal will be horizontally projected. To restore the parts to normal or neutral position with the signal arm 24 retracted, the switch 39 is engaged with the contact 45, which serves to reverse the operation of the motor.

Attention is called to the fact that the switch is only diagrammatically illustrated and in practice, the switch arm 39 will be of such a construction as to engage the desired contact or contacts for a predetermined length of time and then disengage the same, to the end that the various movements of the parts will be accurate and may be predetermined with certainty.

I claim as my invention:—

1. A signalling device of the class described comprising a frame, means pivotally mounting said frame, an extensible signalling means carried by the frame comprising a drum, a normally arcuate flexible signalling member having a portion wrapped flat about the drum, means providing an opening arcuate in cross section adjacent to the drum, one end of said signalling member being fastened to the drum and the other end being free and so disposed as to be projected through said arcuate opening, an electric motor on the frame operable to extend said signalling means, and mechanism operable to energize the motor and to actuate the frame pivotally to vary the position of the signalling means.

2. A signalling structure of the class described comprising a frame, means pivotally mounting the frame, said means having an armature, an

extensible signalling means on the frame comprising a drum, a normally arcuate flexible signalling member having a portion wrapped flat about the drum, means providing an opening arcuate in cross section adjacent to the drum, one end of said signalling member being fastened to the drum and the other end being free and so disposed as to be projected through said arcuate opening, an electric motor operable to extend the signalling means, said motor having a shaft, gearing between the drum and said motor shaft, and means operable to energize the motor and the electromagnetic means so that the latter will attract said armature to vary the angle of the frame and signalling means.

3. A signalling structure of the class described comprising a frame, means pivotally mounting the frame, said means having an armature, a signalling means, an electric motor to actuate the signalling means, gearing operatively connected to the motor and said frame, means operable to energize the motor and the electromagnetic means so that the latter will attract said armature to vary the angle of the frame and signalling means, said signalling means comprising a drum surrounding the motor, a flexible signalling member attached to the drum and normally rolled on the drum, a casing about the drum, said casing having an arcuate opening through which the signalling member is adapted to be projected to assume an arcuate shape, the flexibility of the signalling member in combination with said opening causing the signalling member when projected to assume a straight line.

4. A signalling structure of the class described comprising a frame, means pivotally mounting the frame, said means having an armature, a signalling means on the frame having a drum provided with a hub, an electric motor to actuate the signalling means provided with a shaft, a series of pinions one connected to said hub and another connected to the shaft of said motor, means operable to energize the motor and the electromagnetic means so that the latter will attract said armature to vary the angle of the frame and signalling means, said drum surrounding the motor, a flexible signalling member attached to the drum and normally rolled on the drum, a casing about the drum, said casing having an arcuate opening through which the signalling member is adapted to be projected to assume an arcuate shape, the flexibility of the signalling member in combination with said opening causing the signalling member when projected to assume a straight line, a casing about the drum, rollers in said casing constituting guides for the signalling member.

RAYMOND W. GLAWE.
